UNITED STATES PATENT OFFICE.

HERMANN A. KLEMM, OF NEW YORK, N. Y.

PRESSER-FOOT LIFTING AND LOCKING MECHANISM FOR SEWING-MACHINES.

SPECIFICATION forming part of Letters Patent No. 715,669, dated December 9, 1902.

Application filed November 22, 1901. Serial No. 83,220. (No model.)

To all whom it may concern:

Be it known that I, HERMANN A. KLEMM, a citizen of the United States of America, and a resident of New York city, county and State 5 of New York, have invented certain new and useful Improvements in Presser-Foot Lifting and Locking Mechanism for Sewing-Machines, of which the following is a specification.

My invention is in this example shown in 10 connection with means for lifting the presser-foot by a foot-treadle to enable the operator to have both hands free for adjusting the fabric and holding it until secured by the grip of the presser-foot; and it consists of means 15 for utilizing the guide-arm for the presser, also used in this case as part of said lifting device, in an improved automatic locking device in machines in which the locking-thread looper reciprocates over the presser- 20 foot to prevent lifting the presser-foot or letting it down at any time when the looper occupies a position in which the presser-foot will collide with it in shifting either way to 25 prevent damage to the looper, as hereinafter described, reference being made to the accompanying drawings, in which—

Figure 1 is a front elevation of parts of an overedge sewing-machine, in which my present improvements are represented, with some 30 parts of the machine in vertical section parallel with the plane of the front view. Fig. 2 is an end elevation of the principal parts represented in Fig. 1, with the throat-plate in section. Fig. 3 is a detail in horizontal section on line 1 1 of Fig. 1.

A represents the presser-bar, b the presser-foot, c the looper, and d the hook, which with their operating mechanisms constitute the essential features of an overedge sewing-machine. In the operation of such machines and sewing-machines generally it is sometimes very essential that both hands be employed in adjusting the work to the needle while the presser-foot is up, and it is difficult 45 to retain the work with one hand while releasing the other hand to let the presser-foot down.

On the rear side of the clamp-stud e, attached to the presser-bar A for running in 50 the guide-slot f to maintain the presser-foot in the feed-line, I provide the rearwardly-projecting arm g, reaching through a slot h

in the head i of the supporting-arm j of the machine and a suitable distance beyond, with a lever k pivoted to the side of the supporting-arm j at l, one end of which ranges under the extremity of arm g at m, and the other end is connected by a rod n to a foot-treadle o, located suitably for the operator to lift the presser by his foot. A spring p 60 raises the treadle and releases the lever k from arm g, when the presser-foot is let down. The usual presser-spring will be employed for causing the grip of the presser on the fabric being sewed, and the usual presser-lifting 65 cam-lever q may also be employed for so lifting the presser when desired and for locking the presser in the uplifted position, which is sometimes required. Thus it will be seen that a more convenient means of manipulating the presser generally is provided, besides 70 enabling greater facility in holding the fabric until secured by the presser-foot. Thus having the arm g for lifting the presser by the lever k I now propose to utilize it in such 75 machines as have a looper c, that ranges over the presser-foot in its operation, as part of an automatic locking device to prevent raising the presser-foot or letting it down while the looper is in such position that the presser-foot would collide with and damage the looper, and to this end I employ the reciprocating rod s, operated by the lever t, by which the looper c is operated, so that it is shifted forward synchronously with the forward movement of the looper, and on this rod I provide 80 a prong u, which ranges over said arm g, while the looper ranges over the presser-foot, and thus prevents lifting the presser-foot during such time, and said prong also ranges under 85 said arm when the presser is held up by cam q and prevents dropping the presser onto the looper.

Suitable free space is provided between the upper side of arm g and the lower side of 90 prong u to avoid hindrance to the necessary vertical play of the presser-foot through the lifting caused by the vertical movement of the feed-dog, and there is like space between the under side of said arm and the upper side 100 of lever k, where it acts against said arm, to avoid obstruction to the proper descent of the presser-foot when the feed-dog descends.

An essential advantage of this improved

presser - bar - locking apparatus is that the presser cannot be lifted in any way by hand when the bar is locked, as it can be when it is only the presser-lifting cam-lever that is locked, and thus another element of danger to the looper is avoided.

What I claim as my invention is—

The combination with the presser-bar, the lateral arm of said bar employed for lifting the presser-foot, and with the looper, of the reciprocating rod working synchronously with

the looper, a part of which rod automatically arrests and holds said arm while the looper ranges over or under the presser-foot, to prevent lifting or dropping the presser-foot during such times.

Signed at New York city this 14th day of November, 1901.

HERMANN A. KLEMM.
